ABSTRACT

A high frequency helical filter comprising a conductor case; an input coupling helix; an output coupling helix; and resonance means having a plurality of resonance helices linearly arranged end to end between said input and output coupling helices, each of said resonance helices having an electrical length equal to $\lambda/4$ (λ represents the length of an electromagnetic wave being filtered), wherein the facing ends of the adjacent resonance helices of said resonance means are separately connected or grounded to said conductor case or not grounded at all.

ATTENUATION (dB)

HIGH FREQUENCY HELICAL FILTER

BACKGROUND OF THE INVENTION

This invention relates to a high frequency filter used, for example, with a VHF or UHF telecommunication apparatus. The prior art multistage helical filter includes, as illustrated in FIG. 1, a plurality of resonance helices 2 laterally juxtaposed at a close interval in a conductive case 1. Though the resonance helices 2 thus closely arranged are quite closely coupled, namely, are subject to very little energy loss, the filter as a whole presents an extremely gentle curve of attenuation, resulting in a considerably low degree of filtering. Between the adjacent resonance helices, therefore, are disposed partitions 3 and coupling adjustments 4 to loosen and control their degree of coupling. However, provision of said partitions 3 and coupling adjustments 4 between the respective resonance helices 2 results in a complicated process of manufacturing such type of helical filter and in consequence, high production cost and bulkiness.

SUMMARY OF THE INVENTION

It is accordingly the object of this invention to provide an inexpensive high frequency helical filter of simple, compact construction due to elimination of shields provided, as in the prior art, between the respective resonance helices.

In this specification and in the claims the terms M , N , and m respectively denote the length of helix to be used, the overall length of a plurality of helices and the position where each helix is connected to the conductive case.

According to an aspect of the invention, there is provided a high frequency helical electro-magnetic filter which comprises a conductive case; input coupling means; resonance means having a plurality of resonance helices linearly arranged end to end in said conductor case, and each having an electrical length equal to $n\lambda/4$ (where n is a positive integer and λ represents the length of an electromagnetic wave being filtered), the first resonance helix of said resonance means being coupled to the input coupling means; and an output coupling means coupled to the last resonance helix of said resonance means.

The term "conductor" or "conductive" used herein means an electrical conductor or electrically conductive. The term "coupling" or "coupled" used herein means capacitive or inductive coupling.

BRIEF DESCRIPTION OF THE DRAWINGS

FIG. 1 is a sectional view of the prior art high frequency helical filter;

FIG. 2 is a perspective view, partly in section, of a high frequency helical filter according to an embodiment of this invention;

FIG. 3 presents a schematic arrangement of the helices included in the high frequency helical filter of FIG. 2;

FIG. 4 shows an equivalent arrangement of FIG. 3 where there can be overlooked energy loss occurring between the helices of the high frequency helical filter of FIG. 2;

FIG. 5 briefly illustrates the electromagnetic connection of two helices in the arrangement of FIG. 4;

FIG. 6 indicates an equivalent concentrated constant circuit associated with the arrangement of FIG. 4;

FIG. 7 is an experimentally determined curve diagram showing the attenuation characteristics of the high frequency helical filter of FIG. 2;

FIGS. 8 to 11 shows the arrangements of high frequency helical filters according to other embodiments of the invention;

FIG. 12 is a sectional view of a high frequency helical filter provided with screws for adjusting the capacitive and inductive coupling of helices according to still another embodiment of the invention;

FIG. 13 compares the attenuation characteristics of the high frequency helical filter of FIG. 12 before and after there were used screws for adjusting the capacitive and inductive coupling of the helices;

FIG. 14 is a sectional view of a high frequency helical filter according to a further embodiment of the invention; and

FIG. 15 is a curve diagram showing the attenuation characteristics of the high frequency helical filter of FIG. 14.

DETAILED DESCRIPTION OF THE INVENTION

The high frequency helical filter of this invention has a conductor case 11 having a rectangular prism form as illustrated in FIG. 2. On the opposite crosswise sides of said conductor case 11 are provided terminals 12a and 12b. On a line connecting said terminals 12a and 12b are linearly arranged end to end in tandem an input coupling helix 13, an assembly comprising a first resonance helix 14 and a second resonance helix 15, and output coupling helix 16. The first and second resonance helices 14 and 15 each have an electrical length equal to $\lambda/4$ (λ represents the length of an electromagnetic wave being filtered) and each constitute a $\lambda/4$ resonator. The assembly of resonance helices 14 and 15 therefore have an electrical length of $\lambda/2$. The resonance helix should preferably be formed of, a material little subject to linear expansion such as amber so as to prevent its length from being thermally changed. The input and output coupling helices 13 and 16 are connected at one end to said terminals 12a and 12b respectively. The facing ends of the first and second resonance helices 14 and 15 are separately grounded at substantially the same point on the conductor case 11. It will be noted that the input coupling helix 13 and first resonance helix 14 are capacitively coupled, said first resonance helix 14 and second resonance helix 15 are inductively coupled, and said second resonance helix 15 and output coupling helix 16 are capacitively coupled. Unlike the prior art resonance helices laterally juxtaposed at a close interval, the linearly arranged resonance helices of this invention can be adjusted in capacitive and inductive coupling and resonance frequency simply by changing the pitch distance and physical interval of the respective resonance helices.

FIG. 3 presents a schematic arrangement of the helices included in the high frequency helical filter of the invention. As previously described, the helices 13 and 16 are capacitively coupled with the helices 14 and 15 respectively, and the helices 14 and 15 are inductively coupled with each other. The degree of capacitive and inductive coupling between these helices determines the attenuation characteristics of the high frequency helical filter. The close coupling reduces energy loss, presenting a gentle curve of attenuation, whereas their loose coupling prominently increases energy loss, showing a sharp curve of attenuation, even at the reso-

nance point of the first and second helices 14 and 15. Now let it be assumed that there exists an optimum coupling condition where the helical filter displays sharpest attenuation characteristics, in so far as there can be overlooked energy loss occurring between the respective helices. Under this condition, the arrangement of the helices shown in FIG. 3 may be equivalently represented as illustrated in FIG. 4. Referring to this figure, the first and second resonance helices 14 and 15 are inductively coupled with each other in a region defined by broken lines. This coupled section may be represented as a transformer in the concentrated constant circuit of FIG. 5. With the first and second resonance helices 14 and 15 assumed to have the same electrical properties, the helix arrangement of FIG. 4 may be equivalently illustrated as the concentrated constant circuit of FIG. 6. When determined from the circuit of FIG. 6, the fundamental four port matrix [F] may be expressed as

$$[F] = \begin{bmatrix} 1+Z_1Y_3 & Z_1(2+Z_1Y_3) \\ Y_3 & 1+Z_1Y_3 \end{bmatrix}$$

where:

$$Z_1 = j\omega L_1 + (1/j\omega C_1) \quad Y_3 = 1/j\omega L_3$$

When determined from this matrix, the attenuation constant α may be represented as

$$\alpha = 10 \log_{10} \left[1 + \frac{1}{4} \left\{ \left(\omega L_1 - \frac{1}{\omega C_1} \right) \left(2 + \frac{\omega^2 L_1 C_1 - 1}{\omega^2 L_3 C_1} \right) + \frac{1}{\omega L_3} \right\}^2 \right]$$

In case α is reduced to zero as measured from the above equation, the angular frequency ω_0 may be determined from the following equation:

$$\omega_0 = \left[\frac{2(L_3 + L_1) - C_1}{\pm \sqrt{2(L_1 + L_3) - C_1}^2 - 4L_1(2L_3 + L_1)} \right]^{1/2}$$

Accordingly, when capacitive and inductive coupling is adjusted as in a double tuned circuit, the attenuation pattern of the circuit of FIG. 3 will display a single or double peaks. As apparent from FIG. 7 showing the experimentally determined attenuation curve of the high frequency helical filter of FIG. 2, this invention enables the filter to carry out very good filtration. According to FIG. 2, those ends of the input and output helices 13 and 16 which are not connected to the terminals 12a and 12b are raised above the bottom wall of the conductor case 11, that is, are not grounded. However, even where those ends of both the input and output coupling helices 13 and 16 which are not connected to the terminals 12a and 12b are grounded to the conductor case, as shown in FIG. 8, or where such end of either of said helices 13 and 16 is grounded, there can be obtained desired attenuation characteristics, that is, filtering capacity as indicated by the curve of FIG. 7. Referring to FIG. 8, the input coupling helix 13a and first resonance helix 14a are inductively coupled, the first and second helices 14a and 15a are capacitively coupled, and the second resonance helix 15a and output coupling helix 16a are inductively coupled.

Where the helical filter is desired to present more prominent attenuation, that is, a sharper curve of attenuation, the object is attained by linearly arranging three

or more resonance helices 17a to 17n end to end between the input and output helices 13b and 16b, as shown in FIG. 9, using the fundamental circuit system of FIGS. 3 or 8.

The foregoing description refers to the case where there was used a resonance helix having an electrical length of $\lambda/4$. However, the resonance helix may have an electrical length equal to an integral multiple of $\lambda/4$, that is, $n \lambda/4$ where n is a positive integer, and the assembly of a plurality of such resonance helices can be $N \lambda/2$ or $(2N-1) \lambda/4$ where N is a positive integer. The resonance helix having such a long electrical length presents a larger increase in inductance L than in resistance R , offering the advantage of elevating the quality factor Q ($= \omega L/R$).

FIGS. 10 and 11 indicate filter circuits each including two resonance helices having an electrical length of $\lambda/2$. Referring to FIG. 10, both ends of the resonance helices 24 and 25 are open, and the input and output coupling helices 23a and 26a are open at one end. Further, the input coupling helix 23a and resonance helix 24, as well as the resonance helix 25 and output coupling helix 26a, are capacitively coupled. Referring to FIG. 11, the input and output coupling helices 23b and 26b are grounded at one end, and resonance helices 24a and 25a are each grounded at both ends. Further, the input helix 23b and resonance helix 24a, as well as the resonance helix 25a and output helix 26b, are coupled inductively. Helices arranged as shown in FIGS. 10 and 11 display sharper attenuation curves than in FIG. 7.

As is apparent from the foregoing description of this invention, a resonance helix disposed at a point corresponding to an electrical length of $(2m-1)\lambda/4$ as viewed from that end of the first resonance helix which is capacitively coupled with the input coupling helix is grounded at one end through the conductor case, whereas a resonance helix located at a point corresponding to an electrical length $(m-1)\lambda/2$ is raised at one end above the bottom wall of the conductor case, that is, not grounded. Where the first resonance helix is inductively coupled with the input coupling helix, a resonance helix positioned at a point corresponding to an electrical length of $(m-1)\lambda/2$ as viewed from the inductively coupled end of the first resonance helix is raised at one end above the bottom of the conductor case, whereas a resonance helix placed at a point corresponding to an electrical length of $(m-1)\lambda/2$ is grounded at one end to the conductor case.

Where the aforesaid type of filter is used within a relatively low range of frequency, it is considered necessary for a resonance helix to have a large electrical length. However, this decreases the mechanical stability of the helix and in consequence the performance of a filter as a whole. To avoid such drawback, the helix is customarily fixed in place by inserting thereinto an insulation rod causing very little energy loss which is fitted to the conductor case 11. In this case, the insulation rod may be replaced by a magnetic material giving rise to very little energy loss, for example, ferrite in order to reduce the physical expansion of the helix without changing its electrical length. Unlike the conventional filter comprising laterally juxtaposed resonance helices set apart by, for example, shield plates, the filter of this invention has resonance helices linearly arranged end to end to permit the use of, for example,

a single common insulation rod to plural resonance helices, thus offering great advantage.

Where it is desired minutely to control electromagnetic connection between the helices, there are provided, as shown in FIG. 12, adjustment screws 32 at those parts of a conductor case 31 which face the electromagnetic junctions of adjacent helices. Proper operation of said adjustment screws 32 changes the degree of coupling between the helices, obtaining desired attenuation characteristics. Referring to FIG. 13, a broken line *a* shows a curve of attenuation presented by the helical filter of FIG. 12 when it was not provided with said adjustment screws 32, and a solid line *b* denotes a curve of attenuation corrected from that indicated in the broken line *a*, using the adjustment screws 32. Thus, use of the adjustment screws enables desired attenuation characteristics to be easily obtained.

FIG. 14 illustrates a filter assembly of channel separation type. This type of filter assembly has a conductor case 41 divided by a partition wall 42 into two mutually shielded cavities or unit helical filters 40a and 40b. The unit filters 40a and 40b respectively contain a group of an input coupling helix 43a, resonance helices 44a, 45a and 46a and output coupling helix 47a and another group of an input coupling helix 43b, resonance helices 44b, 45b and 46b and output coupling helix 47b, the elements of both groups being linearly arranged end to end as in the preceding embodiments. Now let it be assumed that the helical filter 40a is set for the passage of signals having a frequency f_1 and the helical filter 40b for that of signals having a frequency f_2 . In this case, the helical filter 40a presents, as viewed from the input terminal 38, a zero impedance for a frequency f_1 and an infinite impedance for a frequency f_2 , while the helical filter 40b indicates, as viewed from said input terminal 38, an infinite impedance for a frequency f_1 and a zero impedance for a frequency f_2 . When, therefore, the input terminal 38 is supplied with signals having frequencies f_1 and f_2 , then there are drawn out signals having frequencies f_1 and f_2 from the output terminals 39a and 39b respectively. FIG. 15 illustrates the curves of attenuation of the above-mentioned channel separation type filter assembly. Where a group of signals has a frequency f_1 ranging from 596 to 602 MHz and another group has a frequency f_2 ranging from 608 to 614 MHz, they can be separated as much as more than 20dB. The signals f_1 and f_2 are subject to energy loss of about 1.5 dB while passing through said filters 40a and 40b. Conversely where the output terminals 39a and 39b are supplied with signals having a frequency f_1 and those having a frequency f_2 respectively, then there can be drawn out from the input terminal 38 two kinds of signals which are free from mutual interference.

This invention is not limited to the aforementioned embodiments, but may be applied in various modifications. Namely, the input and output coupling helices used in the preceding embodiments may be replaced by, for example, coupling discs or loops. Though the foregoing description referred to band pass type helical filters, they may be used as band elimination type by connecting, for example, one end of the input coupling helix to a first transmission line and under this condition either omitting the output coupling helix or connecting one end of the output coupling helix to a second transmission line.

We claim:

1. A high frequency helical electro-magnetic wave filter comprising a conductive casing containing: an input coupling helix; an output coupling helix; a plurality of resonance helices spaced from said casing and coaxially aligned in tandem and separated from each other end-to-end and each having an electrical length of $n \lambda/4$ and the electrical length of said plurality being $N \lambda/2$, the first of said resonance helices in the tandem being physically and conductively separated from, but coupled with, said input helix and the last of said resonance helices in the tandem being physically and conductively separated from, but coupled with, said output helix, each of said resonance helices being conductively connected to the casing at one of its ends which is at the distance from the end of the first resonance helix which is coupled with said input helix, which has an electrical length of $(2m-1)\lambda/4$, wherein m , n and N are positive integers and λ represents the length of an electro-magnetic wave being filtered, said couplings to the input helix and to the output helix being capacitive couplings.
2. A high frequency helical electro-magnetic wave filter comprising a conductive casing containing: an input coupling helix; an output coupling helix; a plurality of resonance helices spaced from said casing and coaxially aligned in tandem and separated from each other end-to-end and each having an electrical length of $n \lambda/4$ and the electrical length of said plurality being $N \lambda/2$, the first of said resonance helices in the tandem being physically and conductively separated from, but coupled with, said input helix and the last of said resonance helices in the tandem being physically and conductively separated from, but coupled with, said output helix, each of said resonance helices being conductively connected to the casing at one of its ends which is at the distance from the end of the first resonance helix which is coupled with said input helix, which has an electrical length of $(m-1)\lambda/2$, wherein m , n and N are positive integers and λ represents the length of an electro-magnetic wave being filtered, said couplings to the input helix and to the output helix are inductive couplings.
3. A high frequency helical filter according to claim 2 in which there is an interspace between each helix and the next adjacent helix and which further includes means for adjusting coupling occurring in at least one of said interspaces.
4. A helical filter according to claim 1 in which there is an interspace between each helix and the next adjacent helix and which further includes means for adjusting coupling occurring in at least one of said interspaces.
5. A high frequency helical electro-magnetic wave filter comprising a conductive casing divided into a plurality of cavities electrically shielded from each other; a plurality of first coupling helices the number of which is the same as the number of said cavities and each of which is connected at one end to a respective one of the cavities; a plurality of second coupling helices; a plurality of resonance helix assemblies, the number of which is the same as the number of cavities, each assembly comprising a plurality of resonance helices located in a respective one of the cavities and spaced from said casing and coaxially aligned in tandem and separated from each other end-to-end and each reso-

nance helix having an electrical length of $n \lambda/4$, the electrical length of each assembly being $(2N-1)\lambda/4$, the first resonance helix in the tandem of each assembly being capacitively coupled with the corresponding one of the first coupling helices, each of said plurality of resonance helices being conductively connected to said casing at one of its ends which is at the distance from the end of the first resonance helix which is capacitively coupled with the first coupling helix, which has an electrical length of $(2m-1)\lambda/4$, the last resonance helix in the tandem of each assembly being inductively coupled with the corresponding one of said second coupling helices, wherein m , n and N are positive integers and λ represents the length of an electromagnetic wave being filtered.

6. A high frequency helical wave filter comprising a conductive casing having within it: a first coupling helix, a resonance helix assembly comprising a plurality of resonance helices spaced from said casing and axially aligned with each other and separated end-to-end

and each having an electrical length of $n \lambda/4$, the length of said assembly being $(2N-1)\lambda/4$; and a second coupling helix spaced from said assembly, the first helix of said resonance helix assembly being capacitively coupled with said first coupling helix, each of said plurality of resonance helices being conductively connected at one of its ends to said casing, the point of said conductive connection of each resonance helix being spaced by an electrical length of $(2m-1)\lambda/4$ from that end of the first resonance helix which is capacitively coupled with said first coupling helix; the last resonance helix of the resonance helix assembly being inductively coupled with said second coupling helix, wherein m , and N are positive integers and λ represents the length of a electromagnetic wave being filtered.

7. A filter according to claim 6 in which there is an interspace between each of said helices and the helix next adjacent and there is means for adjusting coupling occurring in at least one of said interspaces.
